RADIO RECEIVER

Charles S. Root, Fairfield, Conn., assignor to General Electric Company, a corporation of New York

Application July 19, 1943, Serial No. 495,282

11 Claims.

(Cl. 179—1)

My invention relates to radio receivers, more particularly to tone control circuits for such receivers, and has for its principal object a new and improved simple, reliable, and inexpensive tone control arrangement particularly suitable for receivers of the household type.

Tone control circuits are commonly used at the present time for controlling the low, intermediate, and high audio frequency response for radio receivers in order that an individual may select the frequency characteristic most pleasing to him, or correct for the acoustic characteristics of the particular room in which the radio receiver may be located. Such circuits are also useful for removing undesired oscillations, such as noise caused by so-called static or low frequency howl commonly experienced in short wave reception.

Ordinarily, tone control is effected by controlling the low and high frequency response relative to the intermediate frequency response. Theoretically, the ideal way to do this is by means of two individual continuous controls so that both the low and high frequency response may be separately adjusted as desired. In practice, however, it has been found that the provision of two tone controls is not only expensive but also so confusing to the average person that he is quite apt to misuse both of them.

One way of controlling both low and high frequency response with a single control is to provide a switch for selecting separate circuit components providing two or more degrees of low frequency response and other circuit components providing two or more degrees of high frequency response. Four switch positions are required to provide two degrees of low frequency response for each of two degrees of high frequency response. Because of the four fixed positions, such a switch is both expensive and complex, and at best provides only a certain limited number of degrees of response.

It is also possible to provide continuous control of both low and high frequency response with a single control member by connecting a potentiometer in such a way that movement over one-half of its range controls the low frequency response with the high frequency response fixed, while movement over the other half of its range controls the high frequency response with the low frequency response fixed. However, such an arrangement has the disadvantage that the one response must be fixed while the other response is being adjusted. In general, the single value of fixed response is not

an optimum for all values of the variable response.

Experience has shown that a continuous high frequency control is very desirable in order to provide a large selection of values of high frequency response. On the other hand, a continuous control of low frequency response is not always necessary and, in fact, it has been found that two or three values of low frequency response are ordinarily entirely adequate to meet all conditions of operation, particularly when combined with a continuous high frequency control.

Accordingly, it is a further object of my invention to provide a new and improved tone control circuit comprising a single control member movable to select a desired number of degrees of response to one band of audio frequencies and by the same movement continuously to control the degree of response to a second band of audio frequencies and over the same range for each selected degree of response to the first band of frequencies.

It is a further object of my invention to provide a new and improved tone control circuit including a volume control resistor and a manually operable member movable continuously to control the intensity of high frequency oscillations impressed upon said resistor and by the same movement to control the intensity of low frequency oscillations appearing across said resistor.

My invention provides two or more different values of one response and continuous control of the other response over the same range of values for each selected value of the first response all in one control member. By way of example, I have shown the selection of two or more values as applied to the low frequency response and the continuous control applied to the high frequency response.

My invention itself will be more fully understood and its objects and advantages further appreciated by referring now to the following detailed specification taken in conjunction with the accompanying drawing, in which Fig. 1 is a schematic circuit diagram of a radio receiving apparatus embodying my invention in one form; Figs. 2 and 3 are schematic circuit diagrams of radio receiving systems embodying certain other forms of my invention; and Figs. 4 and 5 are graphical representations of certain of the characteristics of my invention.

Referring now to the drawing, I have shown at Fig. 1 a radio receiving apparatus comprising

an antenna 10 for supplying a signal wave for amplification and detection to any suitable receiving and detecting equipment 11. It will be understood that the equipment 11 may comprise amplification and detection means for either amplitude modulated or frequency modulated signal waves, and may be either of the super-heterodyne type or comprise a plurality of stages of radio frequency amplification preceding the detector. The detected output from the source 11, which is of audio frequency varying in accord with voice or music, is impressed across a volume control load resistor 12 having one terminal grounded at 13 and provided with a variable potentiometer slider 14. Across a selectable portion of the volume control resistor 12, the potentiometer slider 14 supplies an audio frequency signal wave to a suitable signal reproducing apparatus 15. The apparatus 15 preferably comprises one or more stages of audio frequency amplification and a signal reproducing device, such as a loud speaker, having a voice coil 15a.

Shunted across a portion of the volume control resistor 12, is connected a "bass compensation" capacitor 16 in series circuit relation with a resistor 17. The capacitor 16 is substantially ineffective for high and intermediate frequency oscillations applied to the volume control resistor 12 by reason of the fact that at these frequencies its impedance is small. However, as is well known, the impedance of the condenser 16 increases with decreasing frequency of oscillation so that for low frequencies the shunt circuit through the capacitor 16 provides a substantially greater impedance than for higher frequencies. The greater impedance of the capacitor 16 for low frequencies increases the low frequency voltage drop across the lower portion of the resistor 12 relative to the high and intermediate frequency voltage drops across the same portion of the resistor. Thus, the volume setting of the slider 14 is effectively higher for low frequency oscillations than for high and intermediate frequency oscillations. In this manner the low, or bass, notes are emphasized.

For the purpose of attenuating only the high frequency oscillations supplied to the volume control resistor 12, an adjustable high frequency by-pass circuit comprising a "high cutting" capacitor 18 is connected in series circuit relation with a potentiometer resistor 19. According to the modification of the invention shown at Fig. 1, the opposite terminals of the potentiometer resistor 19 are connected together and to the capacitor 18, while a brush arm 20, arranged for sliding contact along the resistor 19, is grounded at 21. With this connection, the sections of the potentiometer resistor 19 on opposite sides of the brush arm 20 are connected in parallel circuit relation and in series with the capacitor 18 across the entire volume control resistor 12. By moving the brush arm 20 in either direction from its mid-position, the resistance connected in series with the capacitor 18 may be decreased, thereby to control the effectiveness of the capacitor 18 in bypassing the high frequency oscillations.

The potentiometer slider 20 is arranged to effect by its movement both control of the "high cutting" capacitor 18 and the "bass compensation" capacitor 16. For this purpose, a grounded contact 22 is provided on the sliding brush arm 20 arranged for engagement with a stationary contact ring 23 whenever the brush arm 20 is on a selected side of its mid-position. When the con-

tact 22 is in engagement with the contact ring 23, the capacitor 16 is short-circuited to ground so that the bass compensation described above is ineffective. When the potentiometer arm 20 is on the opposite side of its mid-position thereby to disengage the contacts 22 and 23, the capacitor 16 is rendered operable.

It will now be observed that I have provided a control potentiometer 19, 20 so arranged that 10 when the potentiometer arm 20 is moved to the left from its mid-position, as shown in the drawing, it controls continuously the effectiveness of the "high cutting" capacitor 18 over a predetermined range with the "bass compensation" 15 capacitor 16 in operation. When the potentiometer arm is moved to the right of its mid-position as viewed at Fig. 1, it controls continuously the effectiveness of the capacitor 18 over the same 20 range and also disables the "bass compensation" capacitor 16. One important feature of this arrangement is that it provides one position of the potentiometer arm 20, namely, the extreme right-hand position, where maximum attenuation of both the high frequency and the low frequency 25 oscillations is attained. This position is important for cutting out simultaneously both high and low frequency noises. It also has the effect of reducing the tendency of the receiver to "howl," or produce fluttering sounds due to acoustic 30 feedback between the loud speaker and oscillator, such as occurs frequently during short wave reception. The maximum attenuation of the high frequency oscillation is attained by short-circuiting of the potentiometer resistor 19, and maximum attenuation of the low frequency oscillations is obtained by disabling of the capacitor 16.

The frequency response characteristics of my invention are best illustrated by a group of curves such as those reproduced at Figs. 4 and 5. These 40 curves show the manner in which the voltage on the voice coil 15a, as a measure of sound intensity, varies with frequency for an input wave of predetermined magnitude. Fig. 4 shows a family of curves representing frequency response 45 at various positions of the potentiometer arm 20 to the left of its mid-position (Fig. 1). It will be noted from Fig. 4 that for any position of the arm 20 to the left of its mid-position, the low frequency response is high and substantially unchanged. The relative intensity of the high frequencies is controllable by the potentiometer 19, 20. Fig. 5 shows a similar family of curves representing frequency response at various positions of the potentiometer arm 20 to the right of its 50 mid-position (Fig. 1). Comparison of Figs. 4 and 5 shows that with the arm 20 to the right of center (Fig. 5) the low frequency response is low and substantially the same throughout the entire range of high frequency control, while 55 when the arm 20 is to the left of center the low frequency response is high and substantially the same through the same range of high frequency control.

It will be evident to those skilled in the art 60 that my invention is not limited to the particular potentiometer connection or short-circuiting switch arrangement shown at Fig. 1. At Figs. 2 and 3, I have illustrated certain modifications of my combined high and low frequency tone 65 control member.

The receiving system of Fig. 2, except for the connections of the tone control potentiometer, is similar in all respects to the system shown in Fig. 1 and like parts have been assigned the same 70 reference numerals. At Fig. 2, I have illustrated

a tone control potentiometer including a variable resistor 19a and a manually operable sliding contact 20a cooperating therewith. According to the arrangement herein shown, the mid-point of the potentiometer resistor 19a is connected to the condenser 18 and the manually operable slider 20a is grounded. Thus, with the connections shown at Fig. 2, maximum attenuation of the high frequency oscillations supplied to the resistor 12 is attained when the potentiometer slider 20a is at its mid-position. Movement of the slider 20a to either side of its mid-position increases the resistance in series with the capacitor 18 and decreases the effectiveness of the capacitor 18. It will be noted, however, that as at Fig. 1, the two impedance sections of the potentiometer resistor 19a on opposite sides of the mid-point control the effectiveness of the capacitor 18 over the same range of tone control.

In place of the sliding contact switch of Fig. 1, I have shown at Fig. 2 an overcenter switch comprising a moving switch arm 22a, an overcenter spring 22b, and a stationary contact 23a connected directly to ground. The overcenter switch contact 22a is positioned for actuation by an extension 24 upon the manually operable potentiometer slider 20a. It will now be observed that when the potentiometer arm 20a is moved to the left of its mid-position, as shown in the drawing, the switch contacts 22a and 23a are separated, so that the "bass compensation" capacitor 16 is rendered operable. Thus, with the slider 20a on the left section of the resistor 19a, high frequency tone control is possible over a wide and continuous range with the capacitor 16 in operation. When the potentiometer arm 20a is moved past its mid-position and on to the right side of the potentiometer resistor 19a, as viewed at Fig. 2, it actuates the switch arm 22a into engagement with the grounded contact 23a. Thus, when the slider 20a is on the right side of its mid-position, high frequency tone control over the same predetermined range is possible with the capacitor 16 disabled.

At Fig. 3, I have shown a still further modification of my invention wherein the tone control potentiometer comprises two separate and similar impedance sections, each having one terminal connected to the capacitor 18. Specifically, the potentiometer resistor comprises two separate similar resistor sections 25 and 26 having opposite terminals connected together and to the capacitor 18. In all other respects the arrangement of Fig. 3 is similar to that illustrated in Fig. 2 and like parts have been assigned the same reference numerals. It will be evident almost by inspection that the arrangement of Fig. 3 differs from that of Fig. 2 only in that the potentiometer arm 20a, in moving to the left of its mid-position as viewed in the drawing, decreases the resistance in series with the capacitor 18, and in moving to the right of its mid-position over the resistor section 26 the arm 20a increases the resistance in series with the capacitor 18. According to the arrangement of Fig. 3, the effectiveness of the capacitor 18 is controlled over the same range by each of the resistor sections 25 and 26, as at Fig. 2, but high frequency attenuation is increased in moving to the left and decreased in moving to the right of the mid-position, rather than being decreased in both directions of movement as in Fig. 2. It will be noted that at Figs. 2 and 3 the position of the potentiometer arm 20a at which attenuation of both high frequency and low frequency oscillations is a maximum occurs immediately to

the right of its mid-position, as viewed in the drawing, rather than at the extreme right-hand position as at Fig. 1.

The frequency response curves of Figs. 4 and 5 are, of course, also characteristic of the forms of my invention shown at Figs. 2 and 3. Although I have shown the "high cutting" capacitor 18 connected in parallel circuit relation to the volume control potentiometer 12, it will be apparent to those skilled in the art that this capacitor may with equal facility be connected between other suitable points in the audio frequency circuit and ground.

While I have illustrated only certain preferred embodiments of my invention by way of illustration, many modifications will occur to those skilled in the art and I therefore wish to have it understood that I intend by the appended claims to cover all such modifications as fall within in the true spirit and scope of my invention.

What I claim as new and desire to secure by Letters Patent of the United States is:

1. In combination, a load circuit, means for supplying to said load circuit electric oscillations varying in frequency within a band of audible frequencies in accordance with desired signals, means for attenuating high frequency oscillations supplied to said load circuit, separate means for increasing the intensity of low frequency oscillations with respect to oscillations of higher frequency appearing across said load circuit, manually operable means for continuously controlling the effectiveness of said attenuating means, and switching means operable by attenuation controlling movement of said manually operable means at at least one intermediate point of its range for controlling the effectiveness of said intensity increasing means.

2. In combination, a load circuit, means for supplying to said load circuit electric oscillations varying in frequency within a band of audible frequencies in accordance with desired signals, means for attenuating oscillations supplied to said load circuit at a first frequency within said band, separate means for increasing the intensity with respect to oscillations of other frequencies appearing across said load circuit of oscillations at a second frequency within said band, manually operable means for continuously controlling the effectiveness of said attenuating means, and switching means operable by attenuation controlling movement of said manually operable means at at least one intermediate point of its range of movement for controlling the effectiveness of said intensity increasing means.

3. In combination, a load circuit, means for supplying to said load circuit electric oscillations varying in frequency within a band of audible frequencies in accordance with desired signals, means for attenuating only oscillations of high frequency supplied to said circuit, separate means for attenuating oscillations of high and intermediate frequencies appearing across said circuit, manually operable means for continuously controlling the effectiveness of said first attenuating means, and switching means operable by attenuation controlling movement of said manually operable means at at least one intermediate point of its range of movement for controlling the effectiveness of said second attenuating means to decrease the intensity of low frequency oscillations appearing across said circuit.

4. In combination, a load circuit, means for supplying to said load circuit electric oscillations varying in frequency within a band of audible

5 frequencies in accordance with desired signals, means for attenuating high frequency oscillations supplied to said load circuit, separate means for increasing the intensity of low frequency oscillations with respect to oscillations of higher frequency appearing across said load circuit, manually operable means movable to either side of a predetermined intermediate position continuously to control the effectiveness of said attenuating means within a predetermined range, and switching means controlled by said manually operable means in accordance with its direction of movement from said intermediate position to control said intensity increasing means.

6 5. In combination, a load circuit, means for supplying to said load circuit electric oscillations varying in frequency within a band of audible frequencies in accordance with desired signals, means for attenuating high frequency oscillations supplied to said load circuit, separate means for increasing the intensity of low frequency oscillations with respect to oscillations of higher frequency appearing across said load circuit, manually operable means movable over a range having at least two portions arranged to control the effectiveness of said attenuating means within the same predetermined range of values and switching means controlled by movement of said manually operable means to control the effectiveness of said intensity increasing means within each of said portions of its range of movement.

6 6. In combination, a load circuit, means for supplying to said load circuit electric oscillations varying in frequency within a band of audible frequencies in accordance with desired signals, means for attenuating oscillations supplied to said load circuit at a first frequency within said band of frequencies, separate means for increasing the intensity with respect to oscillations of other frequencies appearing across said load circuit of oscillations at a second frequency within said band, manually operable means movable over a range having at least two similar portions arranged to control the effectiveness of said attenuating means within the same predetermined range of values, and switching means controlled by movement of said manually operable means to control the effectiveness of said intensity increasing means within each of said portions of the range of movement of said manually operable means.

6 7. In combination, a load circuit, means for supplying to said load circuit electric oscillations varying in frequency within a band of audible frequencies in accordance with desired signals, means for attenuating high frequency oscillations supplied to said circuit, separate means for increasing the intensity of low frequency oscillations with respect to oscillations of higher frequency appearing across said load circuit, manually operable means movable to either side of a predetermined intermediate position continuously to control the effectiveness of said attenuating means within a predetermined range, and switching means controlled by said manually operable means in accordance with its direction of movement from said intermediate position for selectively disabling or rendering operable said intensity increasing means.

6 8. In combination, a load circuit, means for supplying to said load circuit electric oscillations varying in frequency within a band of audible frequencies in accordance with desired signals, means for attenuating high frequency oscilla-

tions impressed upon said circuit, separate means for increasing the intensity of low frequency oscillations with respect to oscillations of higher frequency appearing across said circuit, a potentiometer impedance including a manually movable member and having two similar impedance sections on opposite sides of a predetermined intermediate position of said member, each of said impedance sections being connected continuously to control said attenuating means within the same predetermined control range, and switching means controlled by said manually movable member at said intermediate position for disabling said intensity increasing means whenever said manually movable member is on a selected one side of said intermediate position.

6 9. In a radio receiver, a volume control resistor, means for supplying to said resistor electric oscillations varying in frequency within a band of audible frequencies in accordance with desired signals, impedance means including a capacitor connected across at least a portion of said resistor for decreasing the intensity of high and intermediate frequency oscillations appearing across said resistor, means including a potentiometer connected in parallel circuit relation with said resistor for controlling the intensity only of high frequency oscillations appearing across said resistor, said potentiometer including a manually operable member selectively operable with a pair of similar impedance sections arranged on opposite sides of a mid-position of said manually operable member, said impedance sections being connected each continuously to control said high frequency oscillations within the same predetermined range, and switching means actuated by said manually operable member in passing from one of said sections to the other for short circuiting said capacitor whenever said manually operable member is on a selected side of said mid-position.

6 10. In combination, a load circuit, means for supplying to said load circuit electric oscillations varying in frequency within a band of audible frequencies in accordance with desired signals, means for attenuating high frequency oscillations supplied to said circuit, separate means for increasing the intensity of low frequency oscillations with respect to oscillations of higher frequency appearing across said load circuit, a potentiometer including a pair of similar impedance sections and a manually operable member movable within a predetermined range of movement for selective cooperation with said sections, said impedance sections being arranged on opposite sides of a predetermined intermediate position of said manually operable member and being connected continuously to control the effectiveness of said attenuating means in opposite senses and within the same predetermined range as said manually operable member is moved in opposite directions from said intermediate position, and switching means controlled by said manually operable member in accordance with its direction of movement from said intermediate position for selectively disabling or rendering operable said intensity increasing means.

6 11. In combination, a load circuit, means for supplying to said load circuit electric oscillations varying in frequency within a band of audible frequencies in accordance with desired signals, means for attenuating high frequency oscillations supplied to said circuit, separate means for increasing the intensity of low frequency oscilla-

tions with respect to oscillations of higher frequency appearing across said load circuit, a potentiometer including a pair of similar impedance sections and a manually operable member movable within a predetermined range of movement for selective cooperation with said sections, said impedance sections being arranged on opposite sides of a predetermined intermediate position of said manually operable member and being connected continuously to control the effectiveness of said attenuating means in

5 the same sense and within the same predetermined range as said manually operable member is moved in opposite directions from said intermediate position, and switching means controlled by said manually operable member in accordance with its direction of movement from said intermediate position for selectively disabling or rendering operable said intensity increasing means.

CHARLES S. ROOT.
